APPARATUS FOR CLOSING AND OPENING A METAL TUBE

John B. Gill, Box 2127, Torrance, Calif.
Filed Mar. 29, 1962, Ser. No. 183,581
7 Claims. (Cl. 72—416)

The present invention relates to a method and apparatus for closing and opening a metal tube, and more particularly to an improved tube clamping tool or apparatus having die surfaces capable of squeezing a metal tube into a closed position and also die surfaces capable of substantially re-shaping the tube to an open position.

Frequently it is desirable to shut-off metal tubes serving as water lines, gas lines or the like at some point in the line without utilizing main valves that would necessarily shut-off other lines not under repair. It is known that where the pipes are composed of soft metal or other deformable material, the tube may be clamped shut and re-opened with a tool containing dies for this purpose and means for clamping the dies relatively toward each other. Certain tools of this nature have been provided which are satisfactory for the purpose, but which generally require that the dies be removed to convert the tool from the form capable of closing the tube to the form capable of opening the tube. In addition, certain of these tools require partial disassembly in order to position the tool in a clamping position on the pipe or tube.

Other problems which have arisen include the formation of microcracks where the tube is squeezed together and re-opened, and these cracks serve as a weak point for corrosion that will ultimately weaken the tube. Accordingly, it is desirable to provide a clamping tool of this nature in which various improvements are effected to solve these and other problems which have been encountered in this type of tool.

Thus it is a primary object of this invention to provide a clamping tool for closing and opening a permanently deformable tube such as a copper pipe with a pair of dies adapted for easy adjustment of the dies and simplified application of the tool to the pipe.

Another object is to provide a clamping tool of the character described having rounded contacting die surfaces for squeezing the tube shut which minimize injury to the pipe such as the formation of small cracks.

A further object of this invention is the provision of an apparatus for closing and opening a deformable tube which is capable of performing these operations without seriously reducing the capability of the tube for holding high fluid pressures.

Still another object of this invention is to provide an apparatus for closing and opening a deformable tube of the character described which opens the tube to substantially its original shape so as to not unduly restrict the flow of fluids therethrough.

Still another object of the invention is to provide a tool for closing and opening a deformable tube having means for aligning the device on the tube so as to provide a substantially transverse pitching action.

Yet another object is to provide a clamping tool for closing and opening a deformable tube in which the clamping action is effected through a single screw means.

A still further object is the provision of a method for closing and opening a deformable tube in which a clamping device of the above described character is utilized for closing and opening the tube, and in which the clamping tool is replaced while the tube is in the closed position with a simple clamp for holding the tube in such closed position.

Further objects and advantages of my invention will be apparent as the specification progresses, and the new and useful features of my method and apparatus for closing

and opening a metal tube will be fully defined in the claims attached hereto.

In general, any deformable tube may be closed and opened according to the present invention although the invention has been particularly directed to such an operation on copper tubes. It has been found that ordinary copper tubes and even those having relatively thick walls such as are used for standard water pipes may be closed and re-opened according to the invention with substantially no reduction of flow characteristics or pressure retaining ability. However, it is contemplated that this tool may be suitable for use with other tubes or pipes such as polyethylene or other shapable plastics, and even iron, steel or aluminum tubes where the walls are sufficiently thin and the metal is sufficiently deformable to be closed and re-opened by the closing and opening dies of this invention.

The preferred forms of my invention are illustrated in the accompanying drawing forming a part of this specification, in which:

FIGURE 1 is an elevational view illustrating the apparatus for closing and re-opening a deformable tube in position preparatory to squeezing the tube closed and also illustrating the method of utilizing a simple clamp for holding the tube closed so as to free the main tool for closing or re-opening other tubes;

FIGURE 2, a view illustrating the apparatus of this invention as seen in the plane of line 2—2 of FIGURE 1;

FIGURE 3, a view illustrating the auxiliary clamp which may be used in the process form of this invention showing the clamp substantially as seen from line 3—3 of FIGURE 1 with the tube in cross-section as it appears in clamped position;

FIGURE 4, a view similar to that shown in FIGURE 2 except that certain of the parts are broken away and shown in section for the sake of illustration, and the tool is shown in position after closing of the pipe has been effected;

FIGURE 5, a cross-sectional view of certain of the parts shown in FIGURE 4 taken substantially in the plane of line 5—5 thereof;

FIGURE 6, a view better illustrating certain of the parts shown in FIGURE 4 as seen in the plane of line 6—6 thereof, and also illustrating the appearance of the tube as it is closed by the tool of this invention; and

FIGURE 7, a fragmentary view of the clamping tool of this invention in operative position for re-opening the tube and illustrating the manner in which the tube is re-opened.

While I have shown only the preferred forms of my invention, it should be understood that various changes or modifications may be made within the scope of the claims attached hereto without departing from the spirit of the invention.

Referring to the drawings in detail, there is shown a clamping tool or apparatus 11 for closing and re-opening a deformable tube, comprising a frame 12 which is preferably C-shaped as shown herein, and which carries a first section 13 and a second section 14 at a spaced distance from each other. The distance between the first and second section is variable through means 16, which is adapted to move the first section toward and away from the second section, and includes a screw 17 attached for free rotation on the first section by means of a collar 18 rotatably mounted therein. Screw 17 is threadably engaged with said frame by threads 19 which engage the internally threaded collar 20 mounted in the frame, see FIGURE 4. Preferably, screw 17 carries a handle 21 to supply leverage, and the handle preferably includes a ratchet 22 for easy operation. Frame 12 also carries a handle 23 in order to facilitate operation.

Although the preferred form illustrated in the drawings shows a single screw in combination with the above mentioned handles and ratchet, it is apparent that other forms may be used and that more than one screw could be used for clamping. However, the form here shown is preferred, because it provides an efficient operation with a comparatively simple structure. Clamping is effected through screw 17 by engagement of thrust surface 24, see FIGURES 4 and 6, while collar 18 serves to lift the first section operatively as the screw is rotated in reverse.

An essential feature of the clamping tool 11 is the provision of dies 26 and 27 carried on the first and second section respectively and having die surfaces for closing and re-opening a tube when forced relatively together. As shown in the drawings, dies 26 and 27 are both rotatably mounted in their respective positions in frame 12 so that different surfaces of the die may be moved to operative position. Rotation may be effected by knurled handles 28 having slots 29 therein so as to be capable of being turned by hand or by a screwdriver or like tool.

The dies 26 and 27 each include a die member 30 having a laterally extending die surface 31 on one side thereof for squeezing a tube such as copper pipe 32 to a closed position, and a die surface 33 on the other side thereof for opening a tube such as copper pipe 32 which has been squeezed to the closed position, see FIGURE 7. The die surface 31, which is adapted to clamp a tube or pipe closed, has a generally V-shaped cross-section and extends laterally across the full diameter of the pipe. Preferably the apex of the V is rounded into the legs of the V as at 34, see FIGURE 6 in order to avoid sharp corners or edges. It has been found that sharp edges form cuts or grooves into the pipe which form cracks when the pipe is re-opened and the use of rounded surfaces solves this problem.

Die surface 33 which is used for re-opening the pipe, includes a recess 36 having a semi-circular cross-section and adapted to fit over one-half of a pipe. Extending across the die surface 33 in the middle of the recess 36 is a grooved slot 37 adapted to fit over the edge of the pipe at the area where the pipe has been squeezed closed. These grooved slots are important in clamping the pipe within the die so as to return the pipe in proper position where it is being re-opened, and also to prevent the flattened edges of the pipe from being re-opened to such an extent that cracks may develop where the folds occurred.

In order to provide the desired die surfaces in precise position and in order to maintain such precise positions, lock means 38 are provided on each of the sections 13 and 14 of frame 12, see FIGURE 5. As shown herein, each lock means consists of a thumb screw 39 threaded into section 13 or 14 having an end 41 adapted to fit into one of the holes 42 of die 26 or 27. In the embodiment here shown, there are two die surfaces oppositely disposed on each of the dies and therefore holes 42 are similarly disposed 180° from each other.

In order to improve the alignment of the clamping tool 11 and pipe 32 for affecting closing thereof, a guide device 43 is provided on the first section 13, see FIGURES 1 and 2. Guide device 43 is generally U-shaped and adapted to fit over the die of the first section 13 and fit loosely around the screw 17. As best seen in FIGURE 2, guide device 43 has a cut-out 44 on each leg of the U thereof adapted to fit over the pipe 32 and indicates the correct alignment at right angles to the die members of the clamping tool.

Guide device 43 is held against rotation, by fitting over a bifurcated member 46 of the first section 13, and a post 47 which is slidably held in frame 12. Similarly, bifurcated member 46 is held in correct alignment while being free to move toward and away from the second section 14. Correct alignment of bifurcated member 46 provides correct alignment of die 26, because die 26 is rotatably journaled therein. Die 27 is held in correct alignment by

being journaled within flange 48 and bearing 49, both of which are integral with frame 12.

The correct alignment of the pipe and the tool is particularly important to insure that the folds which are formed as the pipe is closed are directly across from each other and perpendicular to the axis of the pipe. If these folds deviate too greatly from the perpendicular, they tend to form weak points as the pipe is re-opened to substantially its original shape. In addition, if the folds are not directly across from each other, the pipe is necessarily somewhat inclined to the die as the pipe is being re-opened.

In operation, the copper tube or similar pipe to be closed is examined and an appropriate place for closing selected by the operator. In the event that the pipe is in the ground, sufficient digging is carried out to allow the clamping tool to be placed in position and the handles operated. With the closing position selected and prepared, the clamping tool 11 is placed on the pipe by opening the screw 39 and positioning dies 26 and 27 so that the V-shaped die surfaces 31 are opposed and locking the die surfaces in position by tightening thumb screw 39 into the appropriate holes 42. The first section is also moved away from the second section if necessary by rotation of screw 17 so as to provide a sufficient opening for the pipe to fit therebetween.

The tool is then placed over pipe 32 as shown in FIGURES 1 and 2 by inserting the pipe 32 through opening 51 in the C frame 12. The proper alignment is made using guide device 43 and clamping is begun by rotating handle 21 while holding the clamp against rotation by means of handle 23, see FIGURE 4. In this way, the first section 13 is forced against second section 14 so that pipe 32 is squeezed flat as shown in FIGURES 4 and 6.

With the pipe thus closed, work may be conducted on the downstream side of the fluid line without loss of material due to leakage, because an exceptionally good shut-off is obtained. When the work to be carried out is comparatively simple, and the off time comparatively short, it may be desirable to leave the shut-off tool in this position while work is being carried out. However, in the event that the work is to be of long duration, or it is desired to use the clamping tool for other jobs, it may be desirable to remove the clamping tool from pipe 32. When the clamping tool is thus removed, the pipe is no longer free from leakage. In such a case an auxiliary clamp 52 may be used.

In general, any clamp which serves to hold the closed sides of the pipe tightly together will be satisfactory, and the clamp shown in FIGURES 1 and 3 is simply illustrative of a clamp that may be used. This clamp 52 comprises a pair of opposed sections 53 having opposed clamping surfaces 54 which are tightly held together by screws 56. As here shown, the screw 56 fits through one section 53 and abuts thereagainst by means of shoulders 57 while threadably engaging the other section.

While it is desired to re-open the pipe, the clamping tool 11 or auxiliary clamp 52 is removed and the clamping tool 11 is adjusted for re-opening the pipe. This adjustment is achieved by opening the first section by unscrewing the screw 17 and opening thumb screws 39 so that the dies 26 and 27 may be rotated. Die surfaces 33 are then brought into opposed position by rotation of dies 26 and 27 through knurled handle 28 and locked in the proper position by tightening thumb screws 39 so that the ends 41 engage in the appropriate holes 42.

With the clamping tool 11 prepared for re-opening the pipe, the tool is slipped on the pipe through opening 51 in the C frame thereof, and an edge of the pipe closure is fitted into the grooved slot 37 of the die surface 33 in the second section 14 of the tool. Handle 21 is then rotated to bring the first section toward the second section with the clamping tool held so that grooved slot 37 of die surface 33 in die 26 engages the other edge of the closed pipe. With both edges so engaged, handle 21 is rotated further

and the pipe begins to re-open as shown in FIGURE 7. Handle 21 is then rotated further until the two die surfaces 33 meet, and at this time the pipe 32 is substantially re-shaped to its original configuration.

As pointed out above, the folded portions of the pipe are not flattened out and in this way the pipe is not completely re-rounded. This is desirable to preserve the strength characteristics of the pipe where the severe fold occurred. However, tests have shown that the frictional effect or pressure drop across a piece of pipe which has been closed and re-opened in this manner is only a matter of say about three feet for a $\frac{3}{4}$ " pipe. This three feet of equivalent pipe length is considerably less than that for most conventional pipe fittings.

From the foregoing description it is seen that I have provided an improved apparatus for opening and closing a deformable tube which is simple in construction and efficient in operation. In addition, it is seen that the use of my tool has very little adverse effect on the pipe closed and re-opened thereby.

I claim:

1. An apparatus for pinching closed and squeezing open a deformable tube, comprising a frame having a first section and a second section at a spaced distance from said first section, a rotatable die pivotally mounted in and carried by said first section, means for moving said first section toward and away from said second section, and a rotatable die pivotally mounted in and carried by said second section for providing opposed die surfaces similar to those of the die in the first section.

2. The apparatus for pinching closed and squeezing open a deformable tube as defined in claim 1, in which the first and second rotatable dies each include a die member having a laterally extending die surface on one side thereof for squeezing a tube to a closed position, said die surface having a generally V-shaped cross section, and a die surface on the other side of said member for opening a tube which has been squeezed to the closed position, said die surface including a recess having a semi-circular cross-section adapted to fit over one-half of a tube and having a grooved slot extending across the die surface in the middle of the recess.

3. The apparatus for pinching closed and squeezing open a deformable tube as defined in claim 1, in which the first and second rotatable dies each include a die member having a laterally extending die surface on one side thereof for squeezing a tube to a closed position, said die surface having a generally V-shaped cross-section, and a die surface on the other side of said member for opening a tube which has been squeezed to the closed position, said die surface including a recess having a semi-circular cross-section adapted to fit over one-half of a tube and having a grooved slot extending across the die surface in the middle of the recess, and lock means for holding the die surfaces of the die members in operative position for closing the tube and in operative position for opening the tube.

4. An apparatus for pinching closed and squeezing open a deformable tube, comprising a generally C-shaped frame having a first section and a second section at a spaced distance from said first section with an open side for easy movement of a pipe laterally between said first and second section, a rotatable die pivotally mounted in and carried by said first section including a first rotatable die member having a plurality of die surfaces, lock means for holding any one of said die surfaces of the first die member in an operative position, a rotatable die pivotally mounted in and carried by said second section including a second rotatable die member having a plurality of die surfaces, lock means for holding any of the die surfaces of said second rotatable die member in operative position, said die surfaces on the first and second die members being similar in configuration, and means for moving said first section toward and away from said second section.

5. An apparatus for pinching closed and squeezing open

a deformable tube, comprising a generally C-shaped frame having a first section and a second section at a spaced distance from said first section with an open side for easy movement of a pipe laterally between said first and second section, a rotatable die pivotally mounted in and carried by said first section including a first die member having a laterally extending die surface on one side thereof for squeezing a metal tube to a closed position, said die surface having a generally V-shaped cross-section with the apex of the V being rounded into the legs of the V, and a die surface on the other side of said first die member for opening a metal tube which has been squeezed to a closed position, said die surface including a recess having a semi-circular cross-section adapted to fit over one-half of a pipe and having a grooved slot extending across the die surface in the middle of the recess, lock means for holding any one of said die surfaces of the first die member in an operative position, a rotatable die pivotally mounted in and carried by said second section including a second die member having a laterally extending die surface on one side thereof for squeezing a metal tube to a closed position, said die surface having a generally V-shaped cross-section with the apex of the V being rounded into the legs of the V, and a die surface on the other side of said second die member for opening a metal tube which has been squeezed to a closed position, said die surface including a recess having a semi-circular cross-section adapted to fit over one-half of a pipe and having a grooved slot extending across the die surfaces in the middle of the insert, lock means for holding any of the die surfaces of said second rotatable die member in operative position, and means for moving said first section toward and away from said second section.

6. The apparatus for pinching closed and squeezing open a deformable tube as defined in claim 5, in which the means for moving said first section toward and away from said second section includes a screw attached for free rotation on said first section and threadably engaged with said frame so as to move the first section with respect to the frame on rotation of the screw.

7. An apparatus for pinching closed and squeezing open a deformable tube, comprising a generally C-shaped frame having a first section and a second section at a spaced distance from said first section with an open side for easy movement of a pipe laterally between said first and second section, a die in said first section including a first die member having a laterally extending die surface on one side thereof for squeezing a metal tube to a closed position, said die surface having a generally V-shaped cross-section with the apex of the V being rounded into the legs of the V, and a die surface on the other side of said first die member for opening a metal tube which has been squeezed to a closed position, said die surface including a recess having a semi-circular cross-section adapted to fit over one-half of a pipe and having a grooved slot extending across the die surface in the middle of the recess, lock means for holding any one of said die surfaces of the first die member in an operative position, a die in said second section including a second die member having a laterally extending die surface on one side thereof for squeezing a metal tube to a closed position, said die surface having a generally V-shaped cross-section with the apex of the V being rounded into the legs of the V, and a die surface on the other side of said second die member for opening a metal tube which has been squeezed to a closed position, said die surface including a recess having a semi-circular cross-section adapted to fit over one-half of a pipe and having a grooved slot extending across the die surface in the middle of the insert, and lock means for holding any of the die surfaces of said second rotatable die member in operative position, a guide device carried on the first section for positioning the pipe in proper alignment in the apparatus, and means for moving said first section toward and away from second section including a single screw attached for free rotation on said first section and threadably engaged

with said frame so as to move the first section with respect to the frame and rotation of the screw, a handle on the clamp, and a lever arm operatively connected for rotation of the screw.
